UNITED STATES PATENT OFFICE.

JOHN H. SHAW, OF NEW HAVEN, CONNECTICUT, ASSIGNOR TO SARGENT & CO., OF NEW HAVEN, CONNECTICUT, A CORPORATION.

HOTEL-LOCK.

1,150,071.

Specification of Letters Patent. Patented Aug. 17, 1915.

Application filed April 10, 1911. Serial No. 620,016.

To all whom it may concern:

Be it known that I, JOHN H. SHAW, a citizen of the United States, residing at New Haven, in the county of New Haven and State of Connecticut, have invented a new and useful Improvement in Hotel-Locks; and I do hereby declare the following, when taken in connection with the accompanying drawings and the characters of reference marked thereon, to be a full, clear, and exact description of the same, and which said drawings constitute part of this specification, and represent, in—

Figure 1 a broken view of the lock in side elevation with the cover removed, both bolts in their retracted positions and the emergency-gate in its clearance position. Fig. 2 a corresponding view showing the inside bolt in its locked position and the emergency-gate in its blocking position. Fig. 3 a broken view in horizontal section, showing the emergency-gate in its clearance position by full lines and in its blocking position by broken lines. Fig. 4 a corresponding view showing the emergency-gate reversed edge for edge in the conversion of the lock from a right-hand door lock to a left-hand door lock. Fig. 5 a detached plan view of the emergency-gate. Fig. 6 a plan view of the guest's key. Fig. 7 a plan view of the maid's or master key. Fig. 8 a plan view of the proprietor's or emergency key.

My invention relates to an improvement in that class of hotel locks which are furnished with a guest's key, a series of maids' or master keys, and a proprietor's or emergency key, the object being to produce a simple, convenient and reliable lock of the character described, constructed with particular reference to being readily converted from a right-hand door lock to a left-hand door lock, and vice versa.

It is also aimed to provide an improved construction and arrangement of movable ward or emergency gate particularly adapted for use in locks of the general type illustrated in Letters Patent No. 898,434, granted to Sargent & Company, on September 15, 1908, as assignee of William J. Carroll, but likewise adapted to locks of other types.

More particularly, the invention contemplates the provision of a reversible ward or emergency gate independent of the bolt to

which it relates, and the improved construction, mounting or arrangement and operation of such ward or gate. 55

To these and other ends, the invention consists in the novel features and combinations of parts to be hereinafter described and claimed. 60

In carrying out my invention as herein shown, I employ what I shall for convenience call an emergency-gate 2 which is reversible edge for edge for the conversion of the lock from a right-hand door lock to a 65 left-hand door lock and vice versa. This gate which, as shown, slides upon the lower wall 3 of the lock-case 4 within said lock case is provided upon one edge at its inner end with a blocking-finger 5 which, in the 70 longitudinal-movement of the gate, is moved so as to obstruct the full and proper entrance into the outside keyway 6 of the lock of all keys except the proprietor's or emergency key 7; the said keyway 6 being formed 75 in the lock-case 4 and partly in the cover 8 thereof.

As herein shown the said gate 2 is formed near its outer end and in its opposite edges with two notches 9 one or the other of 80 which receives, according to the position of the gate, the lower end of an operating-lever 10 resting upon the back of the lock-case 4, turning upon a stud 11 and having its upper end entered into a notch 12 in the lower 85 edge of the upper bolt 13 which is operated only from the inside of the door furnished with the lock and for that reason commonly known in the art as an "inside" bolt.

The lock illustrated is of the general type 90 shown in the above mentioned Carroll patent.

The said inside bolt 13 is provided as usual with a single pivotal lever-tumbler 14 having a gate 15 receiving a post 16 mounted in the inner end of the bolt at a point above the talons 17 and 18 thereof. The said bolt 13 is operated by the guest's key 19 which is inserted in a keyway 20 located above the outside keyway 6 before mentioned 100 and like the same formed in part in the lock-case 4 and in the cover 8 thereof. The keyway 20 is commonly called the inside keyway because it is only accessible from the room-side of the door. As herein shown 105 the tumbler 14 is connected by a coupling-

link 21 with the inner ends of a gang of lever-tumblers 22 mounted upon the outside bolt 23 which is located below the inside bolt 13 and provided with a post 24 entering 5 gatings 25 in the said tumblers 22. The said bolt 23 is formed with the usual talons 26 and 27 for co-action with a series of maids' or master-keys 28 none of which can be operatively introduced into the outside 10 keyway 6 when the inner bolt 13 is in its locked position, since at that time the emergency-gate 2 occupies its blocking position in which its finger 5 obstructs the outside keyway 6 sufficiently to prevent the full or 15 proper introduction into it of any key except the special proprietor's or emergency key 7 designed with particular reference to this lock.

I may now say that my present invention 20 does not concern itself with the particular construction of the inside bolt 13 or of the outside bolt 23, or of any of the parts connected therewith as long as they permit the employment of my improved emergency-gate 2 and its connection with the inside bolt 13 so as to be operated thereby to obstruct 25 the outside keyway 6 when the said inside bolt is in its locked position.

To convert my improved lock from a 30 right-hand door lock to a left-hand door lock, or vice versa, it is necessary only to remove the lock-cover 8 and reverse the gate 2 edge for edge and also to turn the latch-bolt 29 over face for face in the usual manner.

In one adjustment, the plate-like ward or 35 gate is adapted to extend into one end of the keyway or keyhole, and in the other adjustment, *i. e.*, when said ward is turned 40 edge for edge, it is adapted to extend into the keyhole or keyway at the opposite end. When the ward is in blocking position, it 45 not only prevents the operation of the bolt by a certain key or keys, but it even prevents a full insertion or introduction of such key or keys into the lock, and yet the reversibility of the ward or gate permits the lock to be adjusted to the desired functions of the several keys at the respective 50 sides of the lock.

In the use of my improved lock, the guest 55 unlocks the room door by inserting the guest's key 19 into the outside keyway 6 of the lock. When once inside the room, he locks the door by inserting the same key 19 60 into the inside keyway 20. Now by turning the key he throws the inside bolt 13 into its locked position. As the said bolt moves into its locked position, it swings the lever 10 which in turn positively slides the emergency-gate 2 into its obstructing position in which its finger 5 stands across the outside keyway 6 and prevents any key from being fully and properly introduced into 65 the lock from the outside of the door except

the emergency-key 7 which is constructed with particular reference to clearing the blocking-finger 5 of the key. In other words, the blocking-finger 5 of the gate 2 prevents the proper introduction into the 70 lock from the outside, of any of the series of maids' or master-keys designed for use with the lock so that the occupant of the room is secure against intrusion from any one holding any of the maids' or master 75 keys so long as the lock is locked from the inside by the throwing of the inside bolt 13.

What I particularly wish to call attention to is the fact that under my invention it is not necessary to initially construct the locks for use on right hand doors or on left hand doors since all of the locks may be converted by any purchaser for one use or the other by simply removing the lock-cover 8 and reversing the gate 2 edge for edge and reversing the latch-bolt 29 face to face.

Of course I have not attempted to illustrate and describe the numerous modifications of the construction which may be adopted within the scope of the appended 90 claims. In certain aspects of the invention, the kind of lock, *i. e.*, whether provided with one bolt, or with a plurality of bolts, is immaterial. In some aspects of the invention, the particular mounting of the 95 movable ward or gate is the essential feature, and in still others, the reversibility of a ward or gate of the general type herein described.

I claim:—

1. A key-lock having a plurality of keyways and a plurality of bolts, and provided with a removable emergency-gate reversible edge for edge for converting the lock from a right-hand door lock to a left-hand door 105 lock and vice versa.

2. A key-lock provided with a plurality of bolts and a plurality of keyways, and with a removable emergency-gate detachably connected with one of the bolts for operation thereby and arranged to obstruct one of the keyways and reversible edge for edge for converting the lock from a right-hand door lock to a left-hand door lock, and vice versa.

3. In a key-lock, the combination with an inside bolt and an outside bolt, an inside keyway and an outside keyway; of an emergency-gate connected with the said inside bolt for operation thereby to obstruct the outside keyway when the inside bolt is in its locked position, the said gate being reversible edge for edge for converting the lock from a right-hand door lock to a left-hand door lock and vice versa.

4. In a key-lock, the combination with an inside bolt and an outside bolt, an inside keyway and an outside keyway; of an emergency-gate provided with a blocking-finger, and a lever connecting the said gate and 130

inside bolt, whereby the gate is moved into position for its said finger to obstruct the outside keyway when the inside bolt is in its locked position, the said gate being reversible edge for edge for converting the lock from a right-hand door lock to a left-hand door lock, and vice versa.

5. In a lock, the combination of a bolt, a case therefor having a keyway open at opposite sides of the lock, a series of keys for operating said bolt insertable in said keyway, and a device adapted to extend into the keyway at one end to block the operation of at least one of said keys and reversible for changing the hand of the lock; substantially as described.

6. In a lock, the combination of a bolt, a case therefor having a keyway open at opposite sides of the lock, a series of keys for operating said bolt insertable in said keyway, and a device adapted to extend into the keyway at one end to block the operation of at least one of said keys and reversible for changing the hand of the lock, said device comprising a plate-like member adapted to be turned edge for edge; substantially as described.

7. In a lock, the combination of a bolt, a case therefor having a keyway open at opposite sides of the lock, and a ward or gate in the case constructed to project into one end of the keyway but to clear the other end of the keyway, said ward or gate reversible with respect to the keyway to change the hand of the lock; substantially as described.

8. In a lock, the combination of a bolt, a case therefor having a keyway open at opposite sides of the lock, a plurality of keys insertable into said keyway to operate said bolt, a movable device having an operative position in which it prevents the operation of at least one of said keys in said keyhole, but permits the operation of another of said keys in said keyhole, said device being adapted to extend into said keyway at either end of the latter depending upon the adjustment of said device, and means for moving said device into and out of operative position; substantially as described.

50 9. In a lock, the combination of a bolt, a case therefor having a keyway open at opposite sides of the lock, and a sliding ward movable horizontally toward and away from said keyway and having a projection to extend into one end of the keyway, said ward reversible so that said projection may extend into the opposite end of the keyway to thereby change the hand of the lock; substantially as described.

60 10. In a lock, the combination of a bolt, a case therefor having a keyway, said keyway open at both sides of the lock, a plurality of different keys for operating said bolt, a ward in said keyway adapted to permit the operation of one key from one side of the lock but

to prevent the operation of another key at the same side of the lock, said ward being reversible in the keyway to permit the operation of one of said keys from the opposite side of the lock, and to prevent the operation of another key from the opposite side of the lock, and means for moving said ward out of position to block any of said keys; substantially as described.

70 11. In a lock, the combination of a bolt, a case therefor having a keyway open at both sides of the lock, a series of keys for said bolt insertable into said keyway, and a ward movable with respect to said keyway, and adapted when in one position to prevent and permit the operation of two different keys respectively, from one side of the lock, said ward being reversible with respect to the keyway in order to serve the same function relative to said keys at the opposite side of the lock; substantially as described.

80 12. In a lock, the combination of a case having a keyhole, a bolt in said case, a plurality of different keys for operating said bolt insertable into said keyhole, a sliding ward guided between the cap and back plate of the case, and by the wall at the lower edge of the case, and means in the lock case for moving said ward into such position relative to said keyhole that it prevents the operation of said bolt by one of said keys but not by another of said keys; substantially as described.

90 13. In a lock, the combination of a case having a keyhole, a bolt in said case, a plurality of different keys for operating said bolt insertable into said keyhole, a sliding ward guided between the cap and back plate of the case, and by the wall at the lower edge of the case, and means in the lock case for moving said ward into such position relative to said keyhole that it prevents the operation of said bolt by one of said keys but not by another of said keys, said ward reversible with respect to said keyhole to change the hand of the lock; substantially as described.

100 14. In a lock, the combination of a bolt, a case therefor having a keyway open at opposite sides of the lock, and a ward or gate in the case extending into the end portion only of said keyway at one side of the lock, and reversible edge for edge so as to extend into the end portion only of the keyway at the opposite side of the lock; substantially as described.

110 15. In a lock, the combination of a case having a keyway open at both sides of the lock, a bolt in said case, a plurality of keys for operating said bolt, and a movable reversible ward associated with said keyways and adapted to permit and prevent the operation of two different keys respectively, from either side of the lock; substantially as described.

120 16. In a lock, the combination of a bolt,

a case therefor having a keyway open at opposite sides of the lock, a plurality of keys to operate said bolt, a ward associated with said keyway and having an operative position in which it permits and prevents the operation of two different keys respectively, from one side of the lock, said ward reversible to perform the same function with respect to said keys at the opposite side of the lock, and means for moving said ward into

and out of its operative position; substantially as described.

In testimony whereof, I have signed this specification in the presence of two subscribing witnesses.

JOHN H. SHAW.
